(No Model.)

J. DEMAREST.

STATIONARY WASH BASIN.

No. 355,439.

Patented Jan. 4, 1887.

N. PETERS. Photo-Lithographer, Washington, D. C.

UNITED STATES PATENT OFFICE.

JOHN DEMAREST, OF NEW YORK, N. Y., ASSIGNOR TO THE J. L. MOTT IRON WORKS, OF SAME PLACE.

STATIONARY WASH-BASIN.

SPECIFICATION forming part of Letters Patent No. 355,439, dated January 4, 1887.

Application filed October 2, 1886. Serial No. 215,115. (No model.)

To all whom it may concern:

Be it known that I, JOHN DEMAREST, of the city and State of New York, have invented an Improvement in Stationary Wash-Basins, of 5 which the following is a specification.

Wash-basins have been made with a recess at one side, at the bottom of which the waste-pipe is connected, and a tubular overflow and valve have been employed therewith. In cases 10 where the tubular overflow has been guided by the slab to which the basin is connected there has been difficulty in properly attaching the basin to the slab and in guiding the overflow-pipe in such a manner that it will remain 15 in its proper position in relation to the valve-seat and overflow-pipe.

My present invention relates to the combination, with the recessed basin having the waste-pipe at the bottom of the recess and an 20 overflow-pipe and valve, of a bridge attached firmly to the top of the basin at the recess, and forming a guide for the overflow-pipe, and a tubular nut that passes through the marble slab and screws into the bridge, so as to fasten 25 the basin firmly to the slab, and the overflow-pipe passes through the tubular nut, and is removable for cleaning. By this improvement the overflow-pipe and cock and tubular nut are connected properly to the basin in the 30 manufactory, and the plumber is guided thereby in making the proper hole in the marble slab; and the connection of the basin to the slab is facilitated and rendered strong, and the risk of the parts being misplaced is removed.

35 In the drawings, Figure 1 is a vertical section of the basin and parts connected therewith. Fig. 2 is a vertical section at right angles to Fig. 1, the overflow-pipe being in elevation; and Fig. 3 is a plan at the recess of 40 the basin.

The basin A is round or oval, and at one side or corner there is a recess, B, that is adapted to receive the overflow-pipe C and the coupling D for the waste-pipe, and the valve-seat 45 at the upper end of said coupling.

The overflow-pipe and valve are to be of any desired character. I have shown the openings at 3 in the overflow-pipe at the highest water-level for the basin, and the cap E is 50 screwed upon the top of the overflow-pipe and held by a lock-nut, 4.

My special feature of improvement relates

to the metallic bridge G, that is received into the recessed flange 5 at the top edge of the vertical recess B, and this bridge is firmly 55 connected to the basin by the screws 6, passing through the bridge and through holes in the porcelain flange 5 of the basin, where the same is recessed for the reception of said bridge. In this bridge is an opening, the center of 60 which is in line with the center of the waste-pipe coupling, and into this bridge passes the tubular socket H, having a flange to rest upon the marble slab, and said socket is of a sufficient length to pass through the marble slab 65 and the bridge, and to be secured by being screwed into the bridge, or by a nut below the bridge and around the socket. I have shown the socket as screwing directly into the bridge.

The overflow-pipe and its valve can be lifted 70 entirely out of the basin, as the tubular socket is sufficiently large for the passage of the same, and I provide a pin, 10, in the tubular socket H, and a slot, 11, in the cap, having an angle therein that allows the valve and overflow- 75 pipe to be supported by the pin when the same has been sufficiently raised for the discharge of the water.

I claim as my invention—

1. The combination, with the basin having 80 a recess at one side thereof and a recessed or notched flange at the top part, of a metallic bridge and bolts to connect the bridge to the recessed flange, and a flanged socket passing through the slab and into the bridge, so as to 85 connect the basin to the slab, and the overflow-pipe passing through the flanged socket, and the valve at the lower end of the overflow-pipe, and the coupling for the waste-pipe at the bottom of the recess in the basin, sub- 90 stantially as set forth.

2. The combination, with the basin having a recess at one side and a discharge-pipe at the bottom of the recess, of a metallic bridge at the upper end of the recess, and attached 95 to the basin, and a tubular socket to pass through the marble slab and screw into the bridge, substantially as set forth.

Signed by me this 28th day of September, A. D. 1886.

JOHN DEMAREST.
